UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

SHOULDER PAD.

Application filed September 3, 1925. Serial No. 54,309.

To all whom it may concern:

Be it known that I, GEORGE L. PIERCE, a citizen of the United States, and a resident of Brooklyn, in the county of Kings and 5 State of New York, have invented certain new and useful Improvements in Shoulder Pads, of which the following is a specification.

This invention relates to shoulder pads of 10 the type commonly used to protect the shoulders of football players.

The principal objects of the invention are: the provision of such a device of the type described which may efficiently protect 15 the player with the minimum amount of discomfort to the player, which may be readily and cheaply manufactured, and which will present a neat and attractive appearance.

20 Other objects and advantages will appear as the description proceeds.

To this end the invention contemplates the provision of a pad comprising a shoulder portion adapted to overlie the 25 shoulders of a player on both his chest and back, together with a rounded portion adapted to cover the joint of the arm with the shoulder. In each instance the invention contemplates forming the pad of foam 30 rubber, in which the cells of rubber are unbroken. On top of this is placed the heavy leather protective covering, to which is stitched a marginal portion of lighter leather. Directly beneath this lighter 35 leather and adjacent the under edge of the rubber is a marginal or reinforcing strip of light material, and stitching the two marginal strips and the foam rubber together around the periphery of the pad.

40 I have illustrated in the accompanying drawings one embodiment of my invention, although it is to be understood that this merely is for the purpose of making clear the principle involved.

45 In the drawings:—

Figure 1 is a top plan view, partly in section showing one embodiment of my invention.

50 Fig. 2 is a sectional elevation showing the structure of the device in Fig. 1.

Fig. 3 is an enlarged sectional elevation of a detail.

55 Fig. 4 is a sectional view showing the means of fastening the plate and tab together.

Referring now specifically to the drawings, the shoulder portion of the pad is shown to consist of a layer or sheet of foam rubber 1 of any desired thickness, upon which is superimposed a section of heavy 60 protective material 2, such as leather. In order to make the device as light as possible, the heavy leather 2 is cut smaller than the rubber pad 1 and a marginal strip 3 of lighter leather or the like is stitched thereto 65 around its periphery.

Beneath the rubber pad 1 along its edge is provided a reinforcing strip 4. The pad is then stitched through the marginal material 3, rubber 1 and reinforcement 4, the latter 70 part preventing the stitching from cutting through the rubber.

Along one edge of the shoulder pad a strip 5 having eyelets 6 therein is stitched. The opposite side of the pad is likewise 75 provided with an eyeleted strip, as is also the mate of the complete pad, which goes on the opposite shoulder of the player. These two mates are adapted to be laced front and rear, as with lacing 7 in the usual manner. 80

A tab 8 is secured as by stitching to the shoulder pad opposite the neck portion, to which is secured as by lacing 9 or otherwise a joint guard 10 formed in the same way as the pad above described. 85

Overlying the space between the joint guard 10 and the shoulder pad is a plate 11 of heavy leather or the like without padding, which is secured to a tab 12 by lacing 13. The tab 12 is suitably stitched to the protective covering 2. No padding is necessary in the part 11 because it does not come in contact with the player's body. 90

As the cells in the foam rubber pad 1 are unbroken, the pad is absolutely non-absorbent to perspiration or other moisture. As such it will neither chafe or become rotted because of contact therewith. 95

I claim:

1. A device of the type described comprising a shoulder pad and a joint guard, each consisting of a sheet of foam rubber, a heavy protective covering therefor, a lighter marginal strip secured to the protective covering, a reinforcing strip beneath the foam 105 rubber, and stitching passing through marginal strip, rubber and reinforcing strip.

2. A device of the type described comprising a shoulder pad and a joint guard, each consisting of a sheet of foam rubber, a heavy 110

protective covering therefor, a lighter marginal strip secured to the protective covering, a reinforcing strip beneath the foam rubber, and stitching passing through marginal strip, rubber and reinforcing strip, said reinforcing strip extending inwardly but a slight distance from the under edge of the rubber sheet, leaving the under surface of the rubber sheet exposed except for the slight area covered by the reinforcing strip. 15 In testimony whereof I affix my signature.

GEORGE L. PIERCE.
